UNITED STATES PATENT OFFICE.

LEVI H. ROBERTS, OF PARIS, ILLINOIS.

JOURNAL-BOX.

SPECIFICATION forming part of Letters Patent No. 269,714, dated December 26, 1882.

Application filed July 17, 1882. (Model.)

To all whom it may concern:

Be it known that I, LEVI H. ROBERTS, of Paris, in the county of Edgar and State of Illinois, have invented certain new and useful 5 Improvements in Journal-Boxes, of which the following is a full, clear, and exact description.

The object of this invention is to provide a practical anti-friction journal or axle box for railroad-car and other axles or shafts; and it 10 consists principally of journaling two anti-friction wheels or rollers in and between two (front and rear) boxes, which are coupled together and adapted to receive or to be placed upon the journal portion of the axle, with the anti-friction wheels or rollers resting upon the axle and 15 supporting the weight of the car or other load.

The invention also consists of triangular oil-boxes for the journals of the anti-friction wheels or rollers, of the means for coupling 20 the said front and rear boxes together, and of suitable journal-blocks to fit in the front and rear boxes upon the journals of the anti-friction wheels.

Reference is to be had to the accompanying 25 drawings, forming part of this specification, in which similar letters of reference indicate corresponding parts in all the figures.

Figure 1 is a broken elevation of the rear face of the rear box, showing the axle of the 30 car in section. Fig. 2 is a broken elevation of the front face of the front box. Fig. 3 is a broken elevation of the inner face of the front box, showing the axle of the car and the outside journal of one of the anti-friction wheels 35 in section, the outer anti-friction wheel being shown in full elevation. Fig. 4 is a transverse sectional elevation of the complete axle-box, part being broken away to show the dust plate or slides of the journals of one of the anti-friction wheels. Fig. 5 is a front elevation of 40 one of the dust-plates removed from its slot or recess in the box. Fig. 6 is a perspective view of the plates and bolts for coupling the said front and rear boxes together; and Fig. 7 is an 45 end elevation, showing a modification of the end plates and bolts.

A represents the axle of the car; B B, the anti-friction wheels; and C C' represent respectively the front and rear boxes of the axle- 50 box, in and between which the anti-friction

wheels B B are journaled. The anti-friction wheels B B are each formed with the journals b b, which are of a length about equal to the thickness of the boxes C C', and pass through suitable openings formed in the inner or adjacent faces of the boxes, as shown in Fig. 4. The said journals b b of the wheels B B are finished so as to form the collar c at their outer ends and the boss c' at their inner ends, or ends next to the wheel's portion, as shown in 55 the last-mentioned figure. When the wheels are in place in the boxes C C', or rather when these boxes are in place upon the journals of the wheels, the wheels are held in place by the journal-blocks D D, which are placed in the boxes and fit upon the journals between the flanges c and bosses c'. These journal-blocks are made preferably of brass and cast with the ribs d', are segmental in form, and are held in place in the boxes and upon the journals b b of 60 the wheels by the shelves or ledges E E and recess d'', formed upon the inside of the boxes, as shown in Fig. 2.

The front and rear boxes, C C', are in all essential particulars duplicates of each other, except that the rear box, C', is formed with passages a a' through the walls thereof for the passage of the axle A, while the front box, C, is formed with the thrust box or recess E' to receive or fit over the outer end of the axle, as 75 shown in Fig. 4, and that the outer or rear wall of the box C' is made double or formed with the passage d, as shown in Fig. 4. In this passage d is placed the dust plate or slide f, which surrounds the axle A and closes the 80 passage a' in the rear wall of the rear box, C', as shown, and this plate is supported by the axle which it protects, and the passage d is of such height as to permit it to move up or down with the axle with any upward motion of the 85 car, and the plate is of such size as to perfectly close the passage a' at all times.

The inner wall of the front box, C, and also the inner wall of the rear box, C', are made double or formed with the recesses j j and j' j'. 90 In the recesses j j are placed the dust plates or slides g g, and in the recesses j' j' are placed similar dust plates or slides, g' g', as shown in Fig. 4. These plates fit upon the bosses c' c' of the journals of the friction-rollers B B, as 95 100

shown in Fig. 4, and close perfectly the openings *k k* in the inner walls of the boxes, through which the journals of the wheels B B pass, as indicated in said figure, and thus prevent 5 altogether the entrance of dust into the oil-boxes F F, in which the journals *b b* of the wheels B B run.

G G represent plates which rise diagonally from the lower side or bottom of the boxes C C', and form a V-shaped partition in the center of the boxes, as shown in Figs. 2 and 4. These plates give the oil-boxes F F triangular form, as will be understood from Fig. 2, so that the "waste" put in the oil-boxes will be forced 15 nearer to and kept in contact with the journals *b b* as it sinks gradually to the bottom of the boxes.

The oil-boxes are closed by the covers H H, and these covers are formed upon the under 20 side and near the ends with the ribs or downward projections *l l*, which, when the covers are in place, come in front of the journal-blocks D D and prevent them from getting out of place, as will be understood from Figs. 1 and 25 2. The front and rear boxes, C C', are preferably coupled together by means of the upper and lower plates, K K, upper and lower outside clamp-plates, L L, end plates, M M, U-bolts N N, and cross-plates O O, as shown in 30 Fig. 6. The upper and lower plates, K K, are correspondingly guttered upon the inside, as shown at *o o*, to receive the lips *p p*, formed at the upper and lower edges of the boxes, and the side plates, M M, are also correspondingly 35 guttered, as shown at *o' o'* in Fig. 6, to receive the lips *p' p'*, formed at the outer edges of the said boxes, as shown in Figs. 1 and 2; and upon the outside and at the ends of these side plates are formed the claws *q q*, which retain 40 the U-bolts N N, as shown in Fig. 6.

Along the outside of the plates K K are formed the gutters *q' q'*, in which the outside clamp plates, L L, rest, as shown in Fig. 4, which prevent all danger of lateral movement 45 of the plates K K.

All of the parts of the journal-box having been put in place, the cross-plates O O are put upon the U-bolts N N, and the nuts *s s* are then turned upon the threaded ends of the 50 said bolts, and thus clamp all the parts firmly and securely together.

In Fig. 7 plain bolts N' N' are used in place of the U-bolts N N. When these bolts are used, instead of forming the end plates, M M, 55 with the claws *q q*, these plates will be formed with the bolt-passages *t t*, through which the bolts N' N' pass, as shown in said Fig. 7.

The passages *j j* and *j' j'* are made wider at the top than at the bottom, but straight on 60 the inner edges, as indicated in dotted lines in Fig. 3, so that the plates will be free to move upward as the journal-blocks D D wear away, but not toward the center. The outer end of the axle A is formed with the central 65 projection, *v*, as shown in Fig. 4, which receives

the side-thrust of the axle against the wall of the thrust-box E', thus greatly reducing the friction; and the outer ends of the journals *b b* of the anti-friction wheels B B are formed with the central projections, *v' v'*, as shown in 70 said figure, to receive the side-thrust against the outer walls of the boxes C C'.

T is a truss-band placed around the outer end of the front box, C, and T' is a similar band placed around the rear end of the rear box, C', 75 as shown in Fig. 4, for re-enforcing the boxes and protecting them at the outer edges.

By this construction of the axle-boxes it will be seen that the friction and journal motion in the boxes will be greatly reduced, thus increasing the capacity of the motive power and preventing all danger of boxes becoming heated. Besides, the boxes are strong and durable.

Having thus fully described my invention, I 85 claim as new and desire to secure by Letters Patent—

1. The front and rear boxes, C C', in combination with the anti-friction wheels B B, journaled in and between them, the said boxes 90 being coupled together, substantially as and for the purposes set forth.

2. The combination, with the anti-friction wheels B B and front and rear boxes, C C', coupled together, of the journal-blocks D D, 95 substantially as described.

3. The boxes C or C', formed with the diagonal partition-plates G, whereby the oil-boxes F are made triangular in form, substantially as described. 100

4. The coupling for the boxes, consisting of the guttered plates K and M, in combination with the clamp-plates L and bolts N or N', substantially as and for the purposes set forth. 105

5. The end plates, M, formed with the claws *q q*, in combination with the U-bolts N, substantially as and for the purposes described.

6. The front and rear boxes, C and C', formed with the lips *p p'*, in combination with the 110 guttered plates K M, clamp-plates L, and bolts N or N', substantially as and for the purposes set forth.

7. The combination, with the boxes C C', the wheel-journals *b*, and the journal-blocks D D, 115 of the covers H, formed with the ribs *l l*, substantially as and for the purposes set forth.

8. In a journal-box, the combination of the box C or C', having the ledges E, the journal-blocks D, supported upon said ledges at their lower ends, and the cover H, adapted to extend inward opposite the upper end of said blocks D, substantially as and for the purpose set forth. 120

9. The boxes formed with the ledges E, in 125 combination with wheel-journals *b*, the journal-blocks D, and cover H, formed with the ribs *l*, substantially as and for the purposes set forth.

10. The boxes C or C', formed with the tri- 130

angular oil-cups F, substantially as and for the purposes set forth.

11. The combination, with the box having the upwardly-widening slot or opening, of the approximately triangular apertured plate g, as shown and described.

12. The passages j j' for the dust-slide, of plates made wider at top than at bottom, in

combination with the triangular dust plates or slides g g', substantially as and for the purposes set forth.
